VACUUM CLEANER CLEANING ATTACHMENT
OR THE LIKEGeorge H. Frost, Ashland, Ohio, assignor to Westinghouse
Electric Corporation, a corporation of Pennsylvania

Filed Mar. 25, 1964, Ser. No. 79,185

Term of patent 14 years

(Cl. D9—2)

FIG. 2 is a top plan view thereof taken in inverted position from that shown in FIG. 1;

FIG. 3 is a side elevational view thereof taken in inverted position from that shown in FIG. 1;

FIG. 4 is a rear elevational view thereof; and

FIG. 5 is a front elevational view thereof.

I claim:

The ornamental design for a vacuum cleaner cleaning attachment or the like, substantially as shown.
